UNITED STATES PATENT OFFICE.

JAMES A. McLARTY, OF TORONTO, ONTARIO, CANADA.

PROCESS OF TREATING ORGANIC AND INORGANIC MATERIALS.

1,072,751.

Specification of Letters Patent.

Patented Sept. 9, 1913.

Application filed November 20, 1912. Serial No. 732,567.

To all whom it may concern:

Be it known that I, JAMES A. McLARTY, a subject of the King of Great Britain, and a resident of Toronto, Canada, have invented certain new and useful Improvements in Processes of Treating Organic and Inorganic Materials, of which the following is a specification.

My invention relates to improvements in the art of treating materials such as organic or inorganic materials, for the purpose of improving the valuable properties of said materials.

This process may be applied to various substances, for example metals, such as iron or copper, which when so treated acquire the properties of being rust-proof, also of being suitable for use as bearings, in that they will not heat up by friction, also the hardness and density of the metals is increased.

This process may also be applied to organic materials, for example, wood, fabrics, leather and the like, and such materials when so treated become much more stable, that is they resist decay, and also resist the action of molds, bacteria, insect life, worms and other destructive agencies, for a much greater length of time, than the same materials when not so treated.

In carrying out my process, the apparatus illustrated in the annexed drawing may be employed, or other suitable apparatus may be used.

35 In said drawing the figure shows a vertical section of a container suitable for use in carrying out this process.

In said drawing the container D is provided with a perforated shelf C, for supporting the material to be treated, and this container is provided with a hinged lid or cover B, which is provided with a valved outlet A, for allowing the escape of gases, should the pressure in the vessel become excessive.

The receptacle and its contents may be heated either by means of the jacket H which is provided with suitable inlets and outlets, as F and G, for introducing steam, or other hot fluids for heating the contents of the container. In place of this the heater M, which may be a gas or oil burner may be placed below the container for heating the same.

55 In carrying out my process, I place in the

bottom of the container, a mixture containing a carbohydrate, for example sawdust, or wood shavings, or sugar, and a suitable hydrocarbon, such as crude petroleum oil, shown at K.

The perforated partition C is then placed upon the lugs N shown in the drawing and the material to be treated is placed on this perforated partition and the lid B is closed, thereby producing an air-tight receptacle 65 containing the material to be treated, out of contact with the mixture including carbohydrate and hydrocarbon, whereupon heat is applied to the lower part of the receptacle, for the purpose of producing 70 gases capable of effecting the desired changes in the material being treated. The temperature to which the mass of carbohydrate and hydrocarbon is carried, may be from 200 to 400° F., and the length of time 75 during which this temperature is maintained, may be about 1 to 3 hours, depending upon the temperature, size of materials being treated and various other conditions.

The chemistry of the process is rather obscure, and accordingly I deem it advisable not to confine myself to any particular theory, but merely state the actual steps which are performed, and the results which are secured.

80 At the end of the heating period, the heat is removed from the bottom of the container, the valve in pipe A is opened, the lid B is removed from the container, and the materials are taken out, and are ready for 85 shipment or use.

As stated above iron when so treated becomes rust-proof and this property is retained by the iron, even though the same be worked up by heating, into iron objects 95 of any desired shape or size. The iron also is much more malleable and can be welded with great facility.

Copper when treated by this process is made very much harder than ordinary copper, also is rendered especially suitable for use in bearings, since it shows no tendency to heat up. In this connection I will state that bearings of copper and pinion steel have been run at a speed of 1800 revolutions 100 per minute without any lubrication whatever, without generating any heat, and without showing any signs of wear.

105 It is also to be noted that metals when so treated are purified from such substances as 110

phosphorus and the like, which makes the process especially valuable in the treatment of pig iron, high in phosphorus.

5 Coal when treated according to this process, appears to show a considerable increase in its calorific power.

10 Wood and other organic materials, when treated according to this process do not change materially in physical appearance, although it becomes proof against atmospheric influences, and moreover does not check, crack, decay, nor is it subject to insect attack. Wood treated in this manner also burns less readily than untreated wood.

15 This method of treating organic materials is claimed in my copending application 756,031, filed March 21, 1913.

What I claim is:—

20 1. A process of treating materials of the classes set forth, which comprises subjecting said materials in a closed vessel to the action of the gases and vapors evolved by heating a mixture including a carbohydrate and an oil, said mixture being out of contact with said materials.

25 2. A process of treating materials of the classes set forth, which comprises subjecting said materials in a closed vessel to the action of the gases and vapors evolved by heating a mixture including cellulosic material and mineral oil, said mixture being out of contact with said materials.

30 3. A process of treating materials of the classes set forth, which comprises subjecting said materials in a closed vessel to the action of the gases and vapors evolved by heating a mixture including saw dust and crude petroleum, said mixture being out of contact with said materials.

35 40 4. A process of treating materials of the classes set forth, which comprises subjecting

said materials in a closed vessel to the action of the gases and vapors evolved by heating a mixture including a carbohydrate and an oil, said materials being out of direct contact 45 with said mixture, and also out of contact with air.

5. A process of treating metals, to harden the same, and to prevent corrosion thereof, which comprises subjecting said metals to 50 the action of the gases and vapors evolved by heating a mixture including a carbohydrate and crude petroleum, said mixture being out of contact with said metals.

6. A process of treating copper to harden 55 the same, and to remove or reduce the tendency of the same to generate heat by friction, which comprises subjecting said copper to the action of the gases and vapors evolved by heating a mixture including a carbohydrate 60 and crude petroleum, said mixture being out of contact with said copper.

7. A process of treating metals to harden 65 the same, and to prevent corrosion thereof, which comprises subjecting said metals to the action of the gases and vapors evolved by heating a mixture consisting of a carbohydrate and crude petroleum, said mixture being out of contact with said metals.

8. A process of treating copper to harden 70 the same, and to remove or reduce the tendency of the same to generate heat by friction, which comprises subjecting said copper to the action of the gases and vapors evolved by heating a mixture consisting of a carbohydrate 75 and crude petroleum, said mixture being out of contact with said copper.
